assignors to Foster Grant Co., Inc., Leominster, Mass.,
a corporation of Delaware

Filed Mar. 14, 1967, Ser. No. 6,212

Term of patent 14 years

(Cl. D80—9)

FIG. 1

FIG. 3

FIG. 2

FIGURE 1 is a perspective view of the display panel for sunglasses or the like showing our new design;

FIGURE 2 is a cross-sectional view taken on line 2—2 of FIGURE 1; and

FIGURE 3 is a fragmentary rear elevational view thereof.

The fragmentary broken line representation of a display stand and the broken line representation of a sunglasses package in FIGURE 1 are for the purposes of illustration only.

We claim:

The ornamental design for a display panel for sunglasses or the like, substantially as shown and described.
